PANTS AND SKIRT HANGER

Herman P. Fruehauf, 1424 Madrona Drive,
Seattle, Wash.

Filed Oct. 11, 1963, Ser. No. 76,945

Term of patent 14 years

(Cl. D80—8)

FIG. 1

FIG. 2

FIG. 1 is a side elevation view of a pants and skirt hanger showing my new design;

FIG. 2 is a top plan view thereof, and

FIG. 3 is a fragmentary rear elevational view thereof, a portion being omitted for convenience of illustration.

I claim:

The ornamental design for a pants and skirt hanger, as shown.
